ROTATABLE CANISTER UNIT

William D. Taylor, Wooster, Ohio, assignor to Rubbermaid Incorporated, Wooster, Ohio, a corporation of Ohio

Filed Oct. 20, 1967, Ser. No. 9,079

Term of patent 14 years

(Cl. D44—6)

FIG. 1

FIG. 3

FIG. 1 is a top plan view of a rotatable canister unit showing my new design;

FIG. 2 is an elevational view; and

FIG. 3 is a sectional view on line 3—3 of FIG. 1.

I claim:

The ornamental design for a rotatable canister unit, as shown.
